UNITED STATES PATENT OFFICE.

WINTHROP L. JACOBS, OF EAST ORANGE, NEW JERSEY.

DESIGN FOR CARPET.

SPECIFICATION forming part of Design No. 27,084, dated May 18, 1897.

Application filed April 3, 1897. Serial No. 630,656. Term of patent 3 years.

To all whom it may concern:

Be it known that I, WINTHROP L. JACOBS, a citizen of the United States, residing in the city of East Orange, in the county of Essex and State of New Jersey, have invented and produced a new and original Design for a Carpet or other Fabric, of which the following is a specification, reference being had more particularly to the accompanying drawing, illustrating the same and forming part hereof.

The leading feature of my design comprises an oriental pattern of figures of oriental outline containing small ornaments and symmetrically arranged upon the ground.

In the drawing, a is the body, b the border, and a b the complete carpet.

c are the figures of oriental outline.

d are the small ornaments contained in the figures c. The figures c are symmetrically arranged on the ground e.

The design of my invention will be best understood by reference to the accompanying drawing, and it may be expressed in different colors or combinations of colors and applied to velvet, Wilton, Brussels, ingrain, and other carpets.

What I claim as my invention, and desire to secure by Letters Patent, is—

1. In a design for a carpet, the body a, substantially as shown. 30
2. In a design for a carpet, the border b, substantially as shown.
3. The design for a carpet consisting of the body a, and border b, substantially as shown.

In testimony whereof I have hereunto signed my name.

WINTHROP L. JACOBS.
